VENTILATED INSULATING SPACING SHIELD
FOR FLASHLIGHT DRY CELLS

Albert H. Macklenar, Toledo, Ohio

Application December 22, 1949, Serial No. 134,389

1 Claim. (Cl. 240—10.66)

1

This invention relates to a flashlight, and more particularly to a shell for embracing or surrounding the dry cells in a flashlight.

The object of the invention is to provide a shell which is adapted to surround the dry cells in a flashlight, whereby rattling or movement of the dry cells in the flashlight casing will be prevented, and whereby the shell will insure that the dry cells are correctly aligned relative to each other and relative to the light bulb.

Another object of the invention is to provide a shell which is fabricated of an insulating material and which is interposed between the dry cells and casing of a flashlight preventing rattling of the dry cells and insuring that the dry cells make proper contact with each other and with the light bulb, the shell being provided with a plurality of spaced parallel slots for permitting air to circulate around the dry cells so as to prevent overheating thereof.

A further object of the invention is to provide a shell for a flashlight which is extremely simple and inexpensive to manufacture.

Other objects and advantages will be apparent during the course of the following description.

In the accompanying drawings forming a part of this application, and where like numerals are used to designate like parts throughout the same:

Figure 1 is a longitudinal sectional view taken through a flashlight equipped with the shell of the present invention;

Figure 2 is a side elevational view of the shell of the present invention;

Figure 3 is a sectional view taken on the line 3—3 of Figure 5;

Figure 4 is a sectional view taken on the line 4—4 of Figure 5;

Figure 5 is a sectional view taken on the line 5—5 of Figure 2.

Referring in detail to the drawings, there is shown a conventional flashlight indicated generally by the numeral 10. The flashlight 10 includes a cylindrical, hollow casing 11 which has a cap 12 closing its rear end. Mounted on the front end of the casing 11 is a cover 13 which carries a lens 14, Figure 1.

A reflector 18 is arranged within the casing 11 adjacent the front end thereof, and supported in the reflector 18 is the usual light bulb 15 which has the contact point 16. Arranged in end-to-end relation with respect to each other and positioned in the casing 11 is a pair of conventional dry cells 17. Although two dry cells have been shown in Figure 1, it is to be under-

stood that the flashlight may have any desired number of dry cells. For normally urging the dry cells 17 into engagement with the contacts 16 of the light bulb 15, a spring 18' is interposed between the cap 12 and the adjacent end of one of the dry cells 17.

The present invention is directed to a shell 19 which is adapted to be arranged in embracing or surrounding relation with respect to the dry cells 17 and the shell 19 serves to prevent the dry cells 17 from rattling or accidentally moving around in the casing 11. The shell 19 also insures that the dry cells 17 will be maintained in their proper aligned position relative to each other and relative to the contact point 16.

The casing 11, cap 12, cover 13 and reflector 18 are all preferably fabricated of a suitable electricity-conducting metal, and the shell 19 is fabricated of an insulating material, such as fibre, or a suitable plastic material. The shell 19 has a substantially cylindrical shape, and the shell 19 is provided with a plurality of spaced parallel slots 20 which extend longitudinally along the shell 19 for a portion of their length. The slots 20 define therebetween a plurality of spaced parallel ribs 21. The slots 20 serve to permit air to circulate therethrough and around the dry cells 17 so as to prevent the dry cells from sweating or becoming overheated.

Each of the ribs 21 is provided with a plurality of inwardly extending indentations 22 which engage the exterior surfaces of the dry cells 17. The indentations 22 are so arranged as to properly align the dry cells 17 and prevent the dry cells 17 from rattling or moving in the casing 11. The free ends of the shell 19 are spaced from each other so as to define a longitudinally extending channel 23, Figures 4 and 5. The channel 23 provides sufficient clearance whereby the shell 19 can be positioned in the casing 11 without interfering with the usual actuating switch of the flashlight. In other words, the channel or space 23 is adapted to have projecting therethrough the usual flashlight on-and-off switch.

From the foregoing, it is apparent that a shell has been provided which, when arranged in a flashlight, will prevent the dry cells from rattling or moving out of their proper positions. Thus, the shell 19, which is fabricated of an insulating material, is arranged in surrounding relation with respect to the dry cells 17, as shown in Figure 1, and the indentations 22 engage the exterior surfaces of the dry cells 17 so as to hold the dry cells 17 firmly and immobile in the casing 11. The

shell 19 will not interfere with the normal use of the flashlight 10. The slots 20 will enable sufficient air to circulate around the dry cells 17 so as to prevent the dry cells from becoming overheated, and the channel 23 will enable the shell 19 to be inserted in the casing 11 without interfering with the usual on-and-off switch of the flashlight.

The shell 19 can be manufactured in any suitable manner, such as by molding, and the shell 19 has sufficient strength so that it will retain its shape during use. By means of the shell of the present invention, the dry cells 17 and light bulb 15 will have a longer life. If desired, the shell 19 can be fabricated on a punch press. The shell of the present invention maintains the dry cells 17 in contact with each other and also maintains the dry cells in line with the bulb contact point 16.

What is claimed is:

A flashlight comprising a casing, a plurality of dry cells arranged in end to end relation in said casing, a light bulb electrically connected to said casing and dry cells, a shell arranged in surrounding relation with respect to said dry cells for preventing said dry cells from rattling and

for insuring that the dry cells are maintained in alignment, said shell including a plurality of inwardly projecting indentations arranged in engagement with said dry cells, there being a plurality of spaced parallel slots arranged in said shell for the circulation therethrough of air, said indentations being arranged in groups with the indentations in each group arranged in alignment with each other, said shell having its longitudinal free ends spaced from each other to define a channel therebetween, said slots being arranged parallel to the longitudinal axis of said shell, and said indentations having a V-shape.
